INFLATABLE BOUNCE PAD

Mark C. I. Stewart, Ada County, Idaho
(2125 Jackson Bluff Road, Tallahassee, Fla. 32304)

Filed Sept. 25, 1969, Ser. No. 19,299

Term of patent 14 years

Int. Cl. D6—01

U.S. Cl. D15—8

FIG. 1 is a front perspective view of the inflatable bounce pad showing my new design.

FIG. 2 is a top plan view thereof.

FIG. 3 is a side view taken from the opposite side from that shown in FIG. 1.

I claim:

The ornamental design for an inflatable bounce pad, substantially as shown.
